UNITED STATES PATENT OFFICE.

EDWIN E. ARNOLD, OF PITTSBURGH, PENNSYLVANIA, ASSIGNOR TO IRON CITY PRODUCTS COMPANY, OF PITTSBURGH, PENNSYLVANIA, A CORPORATION OF PENNSYLVANIA.

DESIGN FOR A LIFTING-JACK.

55,232.

Specification for Design.

Patented May 25, 1920.

Application filed November 11, 1919. Serial No. 337,266. Term of patent 14 years.

To all whom it may concern:

Be it known that I, EDWIN E. ARNOLD, a citizen of the United States, and residing at Pittsburgh, in the county of Allegheny and State of Pennsylvania, have invented a certain new, original, and ornamental Design for a Lifting-Jack, of which the following is a specification, reference being had to the accompanying drawing, forming a part thereof, Figure 1 of which is a view in perspective looking at the front of a jack

embodying my design, and Fig. 2 is a view in perspective looking at the back of the same.

I claim:

The ornamental design for a lifting jack, substantially as shown.

EDWIN E. ARNOLD.
